WELL DEVICE AND OPERATING MEANS
THEREFORLeonidas C. Miller, Dallas, Tex., assignor to
Eastman Oil Well Survey Company, Dallas,
Tex., a corporation of Delaware

Application March 27, 1939, Serial No. 264,363

22 Claims. (Cl. 255—1)

This invention relates to new and useful improvements in well devices and operating means therefor.

One object of the invention is to provide an improved device which may be readily lowered into a well bore and anchored at any desired elevation therein; said device being adapted to be employed as a well plug or a whip stock to close the bore of the well.

10 An important object of the invention is to provide a well device adapted to be lowered through the column of fluid in the well bore and having improved means which is actuated by the hydrostatic head of the fluid column for anchoring said device in the bore at any desired elevation, whereby the anchoring or locking may be accomplished without the application of an auxiliary pressure.

15 A particular object of the invention is to provide an improved operating means for well devices which includes, a movable piston which is mounted within a normally sealed cylinder whereby the interior of the cylinder is under atmospheric pressure and also whereby the piston may be lowered into the well bore without being effected by the fluid column in said bore, together with means for exposing one end of said piston to the hydrostatic head of the fluid column when the device is properly positioned in the bore, whereby said piston is moved within its cylinder by the hydrostatic head of the column, which actuates the operating means without the necessity of building up an auxiliary pressure in the bore from the surface.

20 Another object of the invention is to provide an improved well device including a body arranged to close the well bore and having retractile anchoring members which are normally in a retracted position, together with a piston for controlling the expansion of said member and being arranged to be actuated by the hydrostatic head of the fluid column in the bore.

25 A further object of the invention is to provide an improved operating means, of the character described, wherein a frangible conductor is connected to one end of the piston cylinder, said conductor being normally sealed to exclude the fluid in the bore from the piston and being adapted to be broken to expose one end of the piston to the fluid column by means of a "messenger" or "go-devil" dropped from the surface; the arrangement assuring that the operating means remains inactive until it is desired to actuate the same.

30 Still another object of the invention is to pro-

vide an improved well device, of the character described, which may be lowered either by a wire line or pipe string and which, after being anchored in the well bore, cannot be removed therefrom, whereby it forms a plug to permanently close the bore of the well; the device lending itself to use as a whip stock since the upper end thereof may be inclined so as to deflect the bit or drill which is subsequently lowered into the bore.

35 A construction designed to carry out the invention will be hereinafter described, together with other features of the invention.

The invention will be more readily understood from a reading of the following specification and 40 by reference to the accompanying drawings, in which an example of the invention is shown, and wherein:

45 Figure 1 is an elevation of an improved device, constructed in accordance with the invention, and showing the same anchored within the well bore, 20

Figure 2 is a transverse, vertical, sectional view of the device, with the anchoring means retracted,

50 Figure 3 is a horizontal, cross-sectional view, 25 taken on the line 3—3 of Figure 2,

Figure 4 is a transverse, vertical, sectional view of the lower portion of the device and illustrating another form of anchoring members.

55 Figure 5 is a view, partly in elevation and 30 partly in section, of the messenger,

Figure 6 is a view similar to Figure 2 of a modified form of the invention,

Figure 7 is a view of the form shown in Figure 6, with the anchoring members moved outwardly to anchoring position, 35

Figure 8 is a horizontal, cross-sectional view, taken on the line 8—8 of Figure 6,

Figure 9 is a view similar to Figure 7, illustrating the device as a well plug, with the anchoring member expanded,

Figure 10 is a view, partly in elevation and partly in section, of the upper portion of the device, showing the conductor to the piston prior to its being broken to allow the fluid in the bore 45 to actuate said piston,

Figure 11 is a horizontal cross-sectional view, taken on the line 11—11 of Figure 9, and

Figure 12 is a sectional detail, showing another form of coupling means between the pipe 50 string and device.

In the drawings, the numeral 10 designates an elongate tapered body which is reduced at its upper end. The lower end of the body is substantially cylindrical in cross-section and is 55

slightly reduced to provide an external annular shoulder 11 (Figure 2). An elongate cylinder 12 surrounds the lower end of the body and is suitably secured thereto by means of welding or otherwise. The cylinder depends axially from the body and has a transverse partition 13 inserted within its lower end. The partition is formed with an external, annular flange which abuts the lower edge of the cylinder. The partition may be welded, or otherwise suitably fastened within the bore of the cylinder.

An axial sleeve 15, which has substantially the same diameter as the cylinder 12, also surrounds the partition 13 below the flange 14 and the upper end of this sleeve is suitably secured to the partition. The lower end of the sleeve 15 is closed by a cylindrical block 16 which is inserted within the bore of the sleeve and is welded, or otherwise fastened therein. A cylindrical housing 17 which may be formed by a short section of pipe is secured to the lower end of the block 16 and depends therefrom. The housing is preferably of the same diameter as the cylinder 12 and sleeve 15 and the lower end of said housing 20 is closed by a suitable conical plug 18 which may be welded into the lower end of the bore thereof. By observing Figure 2, it will be seen that the cylinder 12, sleeve 15 and housing 17, being of the same diameter, provide an elongate casing which depends from the lower end of the body 10.

The cylindrical block 16 is formed with a square bore 19 which extends axially therethrough. A vertical slot 20 projects outwardly from the bore 19 to the exterior surface of the block and a curved locking element or blade 21 has its upper end pivoted on a transverse pin 22, which extends diametrically across the slot. A similar slot 20a is formed in the block 16 on the side opposite the slot 20 and a second locking element or blade 21a has its upper end disposed within the slot 20a. A transverse pin 22a which extends across the slot 20a pivotally secures the upper end of the blade 21 within said slot. When the locking elements or blades are in a retracted position, as shown in full lines in Figure 2, they are disposed within the housing or pipe section 17 and their outer ends do not project beyond the outer diameter of said housing. When in such position, the device may be readily lowered through a well bore A, without said blades or locking elements engaging the wall of said bore.

The locking elements are adapted to be swung outwardly to the position shown in Figure 1, the outer ends of said blades moving outwardly through vertical slots 23 formed in the wall of the housing 17. When in this outward or extended position, the outer tapered ends of the locking elements or blades enter the formation (Figure 1) and serve to lock the device against movement in the well bore. Each locking element is substantially angular in cross-section at its inner end, whereby the edges of said element provide a substantially flat surface, as is clearly shown in Figure 3.

For expanding the locking elements or blades 21 and 21a, an elongate tapered expanding member or head 24 is mounted within the sleeve 15 and is normally in the position shown in Figure 2. The expanding member is shown as substantially rectangular in cross-section and is gradually reduced toward its lower end, whereby said lower end is arranged to engage the flat edges of the locking elements 21 so that upon downward movement of the member the elements are swung outwardly. The expanding member is secured to

the lower end of a piston rod 25 which extends through an axial opening 26 formed in the partition 13. The upper end of the piston rod is disposed within the cylinder 12 and is preferably made integral with a piston 27 which is slidably mounted within the cylinder. The piston includes an annular elastic cup member 28 which is secured to the top of the piston head by means of a retaining disk 29 which is secured to the head by bolts 30. Manifestly, when the piston is moved downwardly within its cylinder 12, the expanding member 24 is moved downwardly between the locking elements 21 and 21a to swing said elements on their pivots 22 and 22a and move the outer tapered ends of said elements outwardly into the formation surrounding the well bore A.

For packing off around the piston rod 25 so as to prevent the pressure from the well bore entering the cylinder 12 below the piston 27, an elastic packing collar 31 surrounds said rod. This collar is secured to the underside of the partition 13 by means of a flanged ring 32 which is fastened to the partition by means of elongate screws 33. With this arrangement, any pressure, which is present in the well bore and which may enter the casing or housing 17 through the elongate vertical slots 23 and then pass upwardly into the sleeve 15, cannot enter the lower end of the cylinder 12 below the piston. Such entrance of any pressure in the bore into the cylinder is prevented by the elastic collar 31 which is preferably formed with an annular lip at its lower end, whereby such pressure acting against the collar forces the same into tight sealing engagement with the outer surface of the piston rod 25.

The extreme upper end of the body 10 is formed with an upwardly extending projection 10' which is substantially vertical and this extension is adapted to be connected with a coupling collar 34, such connection being made by a shear pin 40. The lower end of the well tubing or other string of pipe 36 is threaded into the collar 34 and, thus, it is possible to lower the device through the well bore by means of such string of pipe.

The upper end of the cylinder 12 has an inclined passage 37 leading therefrom and the outer end of this passage has the lower end of a conductor or tube 38 connected therein. The tube is disposed within a vertical groove 39 provided in the wall of the body 10 and said tube extends upwardly to the extension 10' of said body. The extreme upper end of the tube or conductor 38 is bent inwardly and projects through an opening 40 formed in the extension 10' and then through an opening 41 formed in the collar 34, whereby the extreme upper end of said tube is disposed within the bore of the collar. This end of the tube or conductor is normally closed or sealed off, whereby there can be no communication with the interior of the cylinder 12 above the piston, and it is preferable that this end of said tube be constructed of a brittle metal so as to be readily broken.

In the operation of the device, said device is assembled at the surface of the well and the parts are in the position shown in Figure 2. The interior of the cylinder 12 is under an atmospheric pressure and, obviously, the lower end of said cylinder is sealed off by means of the elastic collar 31 which surrounds the piston rod. The upper end of the cylinder above the piston is also sealed off since the upper end of the tube or conductor is closed. Therefore, the pressures on each side of the piston 27 are equalized and since said piston is in its uppermost position, it will remain in

such position due to the frictional engagement of the cups 28 with the wall of the cylinder, together with the frictional engagement of the packing collar 31 with the piston rod. At this time, the locking elements or blades 21 and 21a are in a retracted position.

The device is lowered into the well bore by means of the pipe string 36 and, of course, said well bore contains a column of mud or other fluid. As the device is being lowered through the bore, the pressure of this fluid cannot affect the piston 27 which is sealed off from this fluid and, therefore, during the lowering operation, the piston remains in its uppermost position, which holds the expanding element 24 raised with relation to the expanding blades 21 and 21a.

When the position at which the device is to be set in the bore is reached, the lowering is halted and an elongate weighted rod 42 (Figure 5), commonly known as a messenger, is dropped downwardly through the bore of the pipe string. The lower end of this rod is reduced or tapered and is provided with a plurality of elongate grooves 43 in its exterior surface. As this weighted rod falls downwardly through the bore of the pipe string 36, its lower end strikes the projecting end of the tube or conductor 38 which, as has been explained, projects into the bore of the collar 34. When the weighted rod 42 strikes the end of the conductor, it fractures the same to break off the sealed end of said conductor. The lower reduced end of the rod 42 then seats on an internal shoulder 34' which is formed in the bore of the collar 34. When so seated, fluid may by-pass the rod through the elongate grooves 43 in said rod.

As soon as the end of the conductor 38 is broken off, the hydrostatic head of the fluid in the pipe string 36 and also in the well bore may act through the conductor 38 and against the upper end of the piston 27 within the cylinder 12. The lower end of the piston 27 is under an atmospheric pressure and, therefore, the admittance of the fluid within the bore A to the upper end of the cylinder causes an intermediate downward movement of the piston 27 within its cylinder. It is pointed out that since the underside of the piston is at an atmospheric pressure, the hydrostatic head of the fluid within the bore A and also within the pipe string 36, is sufficient to accomplish lowering of the piston 27, whereby it is not necessary to apply an auxiliary pressure to the column in the pipe string and in the bore.

As soon as the piston 27 moves downwardly, the tapered expanding member or head 24 moves downwardly between the locking elements 21 and 21a and, due to the tapered surface of said member, the elements are swung outwardly through the vertical slots 23 in the housing 17. Downward movement of the piston continues until the upper end of the expanding member 24 engages beneath shoulders 44 which are formed on the inner flat edges of the locking elements or blades 21. When this occurs, it will be obvious that the piston and expanding member cannot be returned to their uppermost position due to the engagement of said shoulders with the upper end of said member, as shown in dotted lines in Figure 1. In such position, the locking elements or blades 21 and 21a have moved outwardly to their fully expanded position and their outer ends are embedded within the formation surrounding the bore A. After the blades have been moved to this position, a downward force may be ex-

erted on the pipe string 36 and such force will fracture the pin 35 which connects the collar 34 to the upper end of the body 10. Such movement of the string will also fracture the tube or conductor 38 adjacent the exterior surface of the collar 34. The pipe string may then be removed from the well and, obviously, the device will remain locked therein. It is noted that the downward pressure exerted when the pin and tube are fractured tends to force the locking elements further into the formation.

The upper end of the body 10 has been shown as inclined or tapered, whereby the device may be used as a whip stock. After the tubing or pipe string 36 has been removed, it will be manifest that a drill pipe having a drill bit at its lower end (not shown) may be lowered through the well bore A and, as the bit strikes the inclined upper edge of the body 10, it will be directed outwardly into the formation to change the direction of drilling.

From the above, it will be seen that a simple and effective means of operating the locking blades is provided. The piston 27 is under an atmospheric pressure and is sealed against outside pressure during the lowering of the device through the well bore. When it is desired to set the device, the messenger or rod 42 is dropped through the pipe string to break off the end of the conductor and expose the upper end of the piston to the hydrostatic head of the fluid column within the bore. This hydrostatic head is sufficient to lower the piston against the atmospheric pressure underneath and, thus, the locking elements 21 and 21a may be expanded outwardly into locking position without the necessity of creating or exerting an auxiliary pressure on the fluid column within the bore.

The locking elements are shown as movable outwardly into the formation around the well bore A and it is noted that said elements could be changed in construction, whereby the device may be locked within a well casing. Such a modification is shown in Figure 4, wherein relatively short locking elements or blades 45 are provided. The upper ends of these locking blades are pivoted on the pins 22 and 22a in the block 16. The lower or outer end of each blade is formed with a sharp point 46 which is adapted to perforate a well casing B, when the locking elements are moved to an expanded position. The blades 45 are provided with a shoulder 47 on their inner edges, which shoulder is adapted to engage over the upper end of the expanding member 24 when the same is moved downwardly between the elements. This shoulder prevents upward movement of the expanding member so as to prevent withdrawal of the same from between the locking blades 45. Manifestly, the operation of this form is exactly the same as the form shown in Figures 1 to 3.

In Figures 6 to 8, a slightly modified form of the invention is shown. In this form, a body 50, similar to the body 10 in Figure 1, is provided and the upper end of this body is arranged to be connected with the pipe string 36 in the same manner as hereinbefore described. The lower end of the body 50 is formed with an axial bore 51, which bore forms a cylinder within the lower end of the body. The upper end of this cylinder communicates through a passage 52 with the lower end of the conductor 38. The lower end of the cylinder 51 is closed by a plug 53 and a piston 54 is movable within the cylinder between the plug and the upper end of said cylinder. The piston

54 is similar in construction to the piston 27 and has a depending piston rod 55 which extends axially through an opening 56 in the plug 53. Immediately below the plug 53, the bore of the cylinder 51 is enlarged and the lower end of this enlarged portion is formed with internal screw threads.

5 An elongate sleeve member 57 is threaded into the lower end of the bore of the cylinder and 10 is formed with an external annular shoulder 58 which abuts the lower end of the body 50. Confined between the extreme upper end of the sleeve 57 and the plug 53 is an elastic packing collar 59 which surrounds the piston rod 55. This collar 15 is retained by a flanged ring 60 which is engaged by the upper end of the sleeve, as is clearly shown in Figures 6 and 7. The sleeve 57 is provided with an axial bore 61 which extends entirely therethrough and a follower member or head 62 is 20 slideable within this bore. The follower has an axial opening through which the piston rod 55 extends.

25 The lower end of the sleeve 57 is provided with a plurality of slots 63 which extend vertically from the lower edge thereof. Four of these slots have been shown and a locking element 64 has its upper end disposed within each slot. A pin 65, which extends transversely of each slot, pivotally mounts the locking element 64 therein. 30 Each locking element has its lower end reduced or tapered to a sharp point and this point is normally confined within a recess 66 provided in a plug 67 which is threaded onto the lower end of the piston rod 55. (Figure 6).

35 Normally, the follower 62 rests on lugs 68 which are formed on the locking element 64 and this follower is held in engagement with said lugs by a coiled spring 69 which is confined between the follower and the retaining ring 60. The spring 40 surrounds the piston rod 55 and is confined within the bore 61 of the sleeve 57. Manifestly, the spring constantly exerts its pressure to urge the follower 62 downwardly, whereby a downward pressure is exerted on the lugs 68 of the locking element 64.

45 The operation of this form is obvious. The parts are assembled at the surface, whereby the cylinder 51 is under an atmospheric pressure. At this time, the piston rod 55 is raised whereby the locking elements 64 have their lower ends engaged within the recess 66 of the plug 67 at the lower end of said piston rod. The spring 69 is, of course, urging the follower 62 downwardly, whereby a pressure is being exerted on the lugs 55 68 of the locking element 64. Such pressure is tending to urge the lower ends of the locking elements outwardly but such movement is prevented by the engagement of said lower ends within the recess 66.

60 When the device is lowered to the position at which it is to be set, the messenger 42 is dropped downwardly through the pipe string 36 and fractures the end of the conductor or tube 38, whereby the hydrostatic head of the fluid in the bore may act downwardly on the upper end of the piston 54. When this occurs, the piston 54 moves downwardly in its cylinder 51, which results in a downward movement of the rod 55. Such downward movement of the piston rod causes the plug 61 to move downwardly with relation to the locking elements 64, whereby the lower ends of said elements are disengaged from the recess 66. Such disengagement of the lower ends of said elements permits the coiled spring 69 to move the follower 70 downwardly to the position shown in Figure 7,

whereby the locking elements 64 are swung radially outwardly and into engagement with the formation surrounding the bore. When swung to this position, it will be evident that the device is locked within the bore against downward movement. The pipe string 36 is then disengaged from the upper end of the device by fracturing the pins 35, as has been explained.

5 In Figures 1 to 3 and 6 to 8, the devices have been shown when used as a whip stock. However, in some instances it might be desirable to utilize the same as a well plug to completely close the bore A. In such instance, the upper end of the body 10 would be substantially flat across the top and its external diameter would be the same 15 throughout its length. When so constructed, it is obvious that the same would serve as a well plug to close the bore when the device was locked in said bore.

20 In Figures 9 to 11, still another form of the invention is shown, whereby the device may be lowered on a cable or other flexible element. In this form, the device is also shown as used as a well plug and, by observing Figure 9, it will be seen that the lower portion of the device includes 25 the cylinder 12, sleeve 15, housing 17 and locking elements 21 and 21a, exactly as in the first form. The piston 27 and expanding member 24 are also identical. However, in this form instead of employing the body 10, a cylindrical body 70 is secured to the upper end of the cylinder 12. This body is formed with an axial bore 71 which extends from the top of the body to a point terminating short of the lower end thereof. The conductor or tube 38 leads from an inclined passage 35 72 which communicates with the upper end of the cylinder upwardly through a recess 73 in the exterior wall of the body. The extreme upper end of the tube is bent inwardly and directed through a radial opening 74, whereby the upper end of said tube is disposed within the bore 71 of the body. This end of the tube is, of course, normally sealed.

40 A cable or other flexible element 75 has its lower end secured in the usual manner to a collar 76, which collar is insertable within the bore 71 of the body. A transversely extending frangible pin 77 connects the collar 76 with the body, whereby the cable may be utilized in lowering the device through the well bore.

45 The operation of this form is substantially the same as the form shown in Figures 1 and 2. The device is lowered by means of the cable 75 with the locking elements in their retracted position and the piston 27 in its raised position, each side of the piston being exposed to atmospheric pressure. When the point at which the device is to be set is reached, lowering thereof is stopped and an elongate sleeve 78 is dropped downwardly 50 on the cable 75. This sleeve slides downwardly on the cable and strikes the end of the conductor 38 to break off said end, as shown in Figure 9. When this occurs, the hydrostatic head of the fluid column within the bore above the device acts downwardly on the upper end of the piston 27 to expand the locking elements 21 and 21a 55 into position. After the device is locked in position, an upward pull on the cable 75 fractures the pin 77 and permits removal of the cable. Obviously, since the diameter of the device is substantially the same as that of the bore A, said device serves as a plug to close said bore.

60 In Figure 12, a slightly modified form of connecting the upper end of the device with the pipe string 36 is shown. In this form, a closed col- 70

lar 78 is threaded onto the lower end of the pipe string 36 and is connected to the upper end of the device by a frangible pin 79. The upper end of the conductor 38 has communication with the bore of the collar 78 and with the bore of the string 36 through an angular plug 80 which is threaded into the collar 78. In this instance, the pressure from the well bore cannot enter the conductor 38 because the lower end of the collar 78 is closed. Therefore, it is possible to run the pipe string dry, that is, with no fluid within said pipe string. Thus, during the lowering operation, the bore of the string is under atmospheric pressure as is the cylinder wherein the piston is operated. After the position at which the device is to be locked within the bore is reached, a suitable fluid may be introduced into the pipe string 36. The hydrostatic head of this fluid column within the pipe string will act downwardly through the conductor 38 to operate the piston and accomplish the setting of the locking elements, as has been described. After the device is set, the frangible pin 79, as well as the angular nipple 80, is fractured to permit removal of the pipe string 36.

It is pointed out that the operating means, which consists of the cylinder and piston, have been shown as actuating the pivoted locking elements. However, it is noted that this operating means may be employed for operating other elements or members, such as core taking tubes or the like, and may be utilized for imparting a force to any object or element within a well bore. The feature of the operating means is the sealing of the interior of the cylinder against pressures outside of said cylinder, whereby the same may be lowered through the well bore and will be maintained under an atmospheric pressure or under a pressure less than the admitted pressure.

The foregoing description of the invention is explanatory thereof and various changes in the size, shape and materials, as well as in the details of the illustrated construction, may be made, within the scope of the appended claims, without departing from the spirit of the invention.

What I claim and desire to secure by Letters Patent is:

1. A well device for closing a well bore including, a body, expansible locking elements mounted in the body and arranged to swing outwardly into locking position, said elements being normally in a retracted position, a cylinder within the body above the elements and normally sealed against the pressure of the fluid in the well bore whereby the interior thereof is under an atmospheric pressure, pressure responsive means movable within the cylinder and associated with the locking elements, and means for exposing one side of said pressure responsive means to the fluid column in the well, whereby the hydrostatic head of the column imparts movement to the piston and actuation of the locking elements may be effected.

2. A well device for closing a well bore including, a body, expansible locking elements mounted in the body and arranged to swing outwardly into locking position, said elements being normally in a retracted position, a cylinder within the body having one end sealed against pressure exteriorly of the cylinder, a frangible normally sealed conductor connected with the other end of the cylinder for closing the same, pressure responsive means movable in the cylinder and associated with the locking elements, and means for breaking the frangible conductor to admit the fluid in

the well bore into one end of the cylinder and against the pressure responsive means, whereby said means is moved and movement of the locking elements into locking position is effected.

3. A well device for closing a well bore including, a body, expansible locking elements mounted in the body and arranged to swing outwardly into locking position, said elements being normally in a retracted position, an actuating member within the body adapted to move between the locking elements to expand the same into locking position, a cylinder within the body having one end sealed against pressure exteriorly of the cylinder, a frangible normally sealed conductor connected with the other end of the cylinder for closing the same, pressure responsive means movable in the cylinder and connected with the actuating member, and means for breaking the frangible conductor to admit the fluid in the well bore into one end of the cylinder and against the pressure responsive means, whereby said means is moved and movement of the locking elements into locking position is effected.

4. A well device for closing a well bore including, a body, expansible locking elements mounted in the body and arranged to swing outwardly into locking position, said elements being normally in a retracted position, an actuating member within the body adapted to move between the locking elements to expand the same into locking position, a cylinder within the body having one end sealed against pressure exteriorly of the cylinder, a frangible normally sealed conductor connected with the other end of the cylinder for closing the same, pressure responsive means movable in the cylinder and connected with the actuating member, means for breaking the frangible conductor to admit the fluid in the well bore into one end of the cylinder and against the pressure responsive means, whereby said means is moved and movement of the locking elements into locking position is effected, and co-acting means on the actuating member and locking elements in an expanded position to prevent removal of the device from the bore.

5. A well device including, a body arranged to be lowered into a well bore to close said bore, expansible locking elements mounted in the body and normally in a retracted position, an actuating member within the body for moving the elements outwardly into engagement with the wall of the bore, a pressure responsive means connected with the actuating member and normally maintained under an atmospheric pressure, and means for exposing one side of the pressure responsive means to the fluid column in the well bore, whereby the hydrostatic head of said column moves said member to expand the locking elements into locking position.

6. A well device including, a body arranged to be lowered into a well bore to close said bore, expansible locking elements mounted in the body and normally in a retracted position, an actuating member within the body for moving the elements outwardly into engagement with the wall of the bore, a cylinder above the actuating member normally sealed against pressure in the well bore whereby the interior of the cylinder is under atmospheric pressure, a pressure responsive means with the cylinder and connected with the actuating member, and means for exposing one side of the pressure responsive means to the pressure of the fluid column in the well, whereby the hydrostatic head of said column moves said means to

operate the actuating member and expand the locking elements to their locking position.

7. A well device including, a body arranged to be lowered into a well bore to close said bore, expandable locking elements mounted in the body and normally in a retracted position, an actuating member within the body for moving the elements outwardly into engagement with the wall of the bore, a pressure responsive means connected with the actuating member and normally maintained under an atmospheric pressure, means for exposing one side of the pressure responsive means to the fluid column in the well bore, whereby the hydrostatic head of said column moves said member to expand the locking elements into locking position, and co-acting means on the actuating member and locking elements in an expanded position to prevent removal of the device from the bore.

20 8. A well device including, a body arranged to be lowered into a well bore to close said bore, expandable locking elements mounted in the body and normally in a retracted position, an actuating member within the body for moving the elements outwardly into engagement with the wall of the bore, a cylinder above the actuating member normally sealed against pressure in the well bore whereby the interior of the cylinder is under atmospheric pressure, a pressure responsive means with the cylinder and connected with the actuating member, means for exposing one side of the pressure responsive means to the pressure of the fluid column in the well, whereby the hydrostatic head of said column moves said means to operate the actuating member and expand the locking elements to their locking position, and co-acting means on the actuating member and locking elements for maintaining the locking elements in an expanded position to prevent removal of the device from the bore.

40 9. A well device adapted to close a well bore including, an elongate body arranged to be connected to a lowering means by a frangible pin, pivoted locking elements mounted in the body and normally in a retracted position to permit lowering of said body through the bore, a tapered expanding member arranged to move between the elements to expand the same, said member normally being out of engagement with the elements, 50 a movable piston mounted in the body connected with the expanding member and normally under atmospheric pressure, and means for exposing one side of the piston to the fluid column above the device for effecting movement of the piston, whereby the expanding member is moved between the locking elements to swing the same to their locking position.

60 10. A well device adapted to close a well bore including, an elongate body arranged to be connected to a lowering means by a frangible pin, pivoted locking elements mounted in the body and normally in a retracted position to permit lowering of said body through the bore, a tapered expanding member arranged to move between the elements to expand the same, said member normally being out of engagement with the elements, 65 a movable piston mounted in the body connected with the expanding member and normally under atmospheric pressure, means for exposing one side of the piston to the fluid column above the device for effecting movement of the piston, whereby the expanding member is moved between the locking elements to swing the same to their locking position, and co-acting means on the expanding member and locking elements for pre-

venting retraction of the member from between the elements to maintain said elements in locking position.

5 11. A well device adapted to close a well bore including, an elongate body arranged to be connected to a lowering means by a frangible pin, pivoted locking elements mounted in the body, retaining means engaging the elements in a retracted position, a piston connected with the retaining means and normally under an atmospheric pressure, means for exposing one side of the piston to the fluid column above the device, whereby the hydrostatic head of said column moves the piston to disengage the retaining means from the locking elements, and spring- 10 pressed means for moving the locking elements to their locking position as soon as said retaining means is disengaged therefrom.

12. As a sub-combination in a well device, a pressure actuated means including, a cylinder 20 having one end sealed against pressures outside said cylinder, a frangible sealed conductor leading from the opposite end of the cylinder, whereby the interior of the cylinder may be maintained under atmospheric pressure while being lowered 25 through the well, and a piston within the cylinder arranged to undergo movement when the frangible conductor is broken and outside pressures are admitted to one end of the cylinder.

13. An operating means, of the character described, including, a cylinder, a piston movable within the cylinder and having a piston rod projecting from one end of the cylinder, means for closing the end of the cylinder and sealing off around the piston rod, and frangible means for 30 normally closing the other end of the cylinder against pressure outside of the cylinder, whereby the interior of the cylinder may be maintained under an atmospheric pressure while being lowered into a well bore after which the frangible means may be broken to admit outside pressure 35 into the interior of the cylinder to move the piston.

40 14. An operating means, for well devices, including, a cylinder having closed ends, one of said ends having an opening therein which is normally closed by a frangible element, and a piston movable in said cylinder and normally under atmospheric pressure and arranged to be moved therein when the frangible element is broken to admit outside pressure to the interior of the cylinder.

45 15. A well device arranged to be lowered in a well bore including a body, expansible elements mounted in the body and arranged to be moved outwardly into the wall of the bore, said elements being normally in a retracted position, a cylinder within the body above the elements and normally sealed against the pressure of the fluid in the well bore whereby the interior thereof is 50 at a pressure less than the pressure of said fluid, pressure responsive means within the cylinder and associated with expansible elements, and means for exposing one side of said pressure responsive means to the fluid column in the well, 55 whereby the pressure of said fluid imparts movement to the piston to move the elements to their expanded position.

60 16. A well device for closing a well bore including, a body, expansible locking elements mounted 70 in the body and arranged to swing outwardly into locking position, said elements being normally in a retracted position, a cylinder within the body having one end sealed against pressure exteriorly 75 of the cylinder, means for closing the opposite

end of the cylinder, pressure responsive means movable in the cylinder and associated with the locking elements, and means for removing the cylinder closing means to admit the fluid in the well bore into one end of the cylinder and against the pressure responsive means, whereby said means is moved and movement of the locking elements into locking position is affected.

17. A well device arranged to be lowered in a well bore including, a body, expandible elements mounted in the body and arranged to be moved outwardly into the wall of the bore, said elements being normally in a retracted position, a cylinder within the body having one end sealed against the pressure exteriorly of the cylinder, means for closing the opposite end of the cylinder, pressure responsive means movable in the cylinder and associated with the expandible elements, and means for removing the cylinder closing means to admit the fluid in the well bore into one end of the cylinder and against the pressure responsive means, whereby said means is moved and movement of the expandible elements into their expanded position is affected.

18. A well device arranged to be lowered through an uncased well bore including, a body, elongate curved locking elements mounted in the body and arranged to move outwardly into the formation, the end of each element being curved to facilitate its entry into the formation, said elements being normally in a retracted position, a cylinder within the body above the elements and normally sealed against the pressure of the fluid in the well bore whereby the interior thereof is under pressure less than the pressure of the fluid in the well bore, pressure responsive means movable within the cylinder and associated with the locking elements, and means for exposing one side of said pressure responsive means to the fluid column in the well, whereby the hydrostatic head of the column imparts movement to the piston and actuation of the locking elements may be effected.

19. A well device arranged to be lowered through the well casing in a well bore including, a body, pivoted locking elements mounted on the body and arranged to be moved outwardly to puncture the well casing, the leading end of each element being pointed and sharpened to facilitate its passage through the casing, said elements being normally in a retracted position, a cylinder

der within the body above the elements and normally sealed against the pressure of the fluid in the well bore whereby the interior thereof is under pressure less than the pressure of the fluid in the well bore, pressure responsive means movable within the cylinder and associated with the locking elements, and means for exposing one side of said pressure responsive means to the fluid column in the well, whereby the hydrostatic head of the column imparts movement to the piston and actuation of the locking elements may be effected.

20. As a sub-combination in a well device, a pressure actuated means including, a cylinder having one end sealed against pressure outside said cylinder, closure means for sealing the opposite end of the cylinder, whereby the interior of the cylinder may be maintained under a pressure less than the pressure in the well while being lowered through said well, and a pressure responsive member arranged to undergo movement when the closure means is opened and outside pressures are admitted to one end of the cylinder.

21. An operating means, of the character described, including a housing, a pressure responsive element movable within the housing and having an actuating rod projecting from one end of the housing, means for closing the end of the housing and packing off around the rod, and a closure for normally sealing the opposite end of the housing against pressure outside of the housing, whereby the interior of said housing may be maintained under a pressure less than the pressure outside of the housing while being lowered into a well bore, after which the closure means may be opened to admit outside pressure into the interior of the housing to move the pressure responsive means.

22. An operating means for well devices including, a cylinder having closed ends, one of said ends having an opening therein, closure means for normally sealing said opening, and a piston movable in said cylinder and normally under a pressure less than the normal pressure outside of the cylinder and arranged to be moved within the cylinder when the closure means is opened to admit said outside pressure to one side of the piston.
